DISPLAY TRAY

Joseph Edgar Bouchard, Quebec,
Quebec, CanadaApplication August 28, 1946, Serial No. 693,529
In Canada July 30, 1946

7 Claims. (Cl. 211—114)

1

The present invention relates to trays for displaying merchandise in stores, and particularly trays adapted for suspension from a movable support with freedom for movement relative to said support about a horizontal suspension axis. The support may comprise a pair of chains running over wheels and supporting a number of suspended trays.

The general object of the present invention is to provide an improved tray adapted for the above mentioned use. A more specific object of the invention is to provide a suspension tray with a counter-balance adjustable to maintain the merchandise supporting platform of the trays in a horizontal position when the merchandise is so placed on the platform that the weight tends to tilt the platform out of a horizontal position. In a preferred form of the invention, the counter-balance is in the form of a bar beneath the tray platform and supported by flange portions of the tray structure which form guideways at opposed sides of the frame for the ends of the bar so that the latter may be adjusted in a horizontal direction transverse to the length of the bar. The merchandise supporting platform of the tray may consist of a panel formed of glass or other suitable material mounted on the flanges forming the upper walls of said guideways.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described a preferred embodiment of the invention.

Of the drawings:

Figure 1 is a perspective view of a tray constructed according to the invention;

Figure 2 is a section on the line 2—2 of Fig. 1;

Figure 3 is a detail section on the line 3—3 of Figure 1;

Figure 4 is a fragmentary perspective view; and

Figure 5 is an elevation of an assembly of trays in moving display.

The tray construction illustrated in the drawings comprises a hollow or open frame 1, ordinarily rectangular as shown, which may be formed of metal or other suitable material, and which is L-shaped in cross section. As is indicated in Figs. 2 and 3, the base flange portions of the L-shaped cross sections of each two op-

2

posed sides of the frame extend inwardly toward one another. Along two opposed sides of the tray, which may be regarded as the ends of the frame, are provided inwardly extending horizontal flanges 3 spaced slightly above and parallel to the base 2 for a purpose that will presently be described. A sheet of glass or other material 5 is laid upon the flanges 3 to constitute the bottom of the tray.

- 10 From the ends of the frame, and at the midpoints thereof, posts 6 extend upwardly for suspension. The upper end of each post 6 is formed with a keyhole slot 7 for attachment to a headed member from which the tray is to be suspended.
- 15 When the tray is suspended, the bottom side thereof will not lie horizontal unless the load is suitably distributed on both sides of the longitudinal medial plane. Inasmuch as the display in most cases will not be so balanced, a counter-
20 balance means is provided. This consists of a bar 8 having its ends slidably received beneath the flanges 3, as shown in Figure 4. The load is balanced merely by shifting the bar 8 in one direction or the other as indicated by the double
25 arrow shown in Figure 4.

In Figure 5 is illustrated an example of a display installation according to the invention. A double chain 9 is trained over a pair of upper and lower pulleys 10 and 11. The trays are suspended from and between the chains by being attached at the keyhole slots 7 to headed members 12 carried by the chains. One of the wheels 10, 11 may be driven by a motor or other suitable means. The articles displayed in the respective trays, being balanced by the bars 8 in the manner set forth maintain a steady position on the trays notwithstanding the movement of the latter with the chains.

While in accordance with the provisions of the 40 statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

50 Having now described my invention, what I claim as new and desire to secure by Letters Patent, is:

1. A tray comprising a frame having separate goods and counter-balance supporting means, 55 means for suspending the frame in a medial

bisecting plane to turn about an axis above said supporting means, and a counter-balance slidable on said counter-balance supporting means perpendicularly to said plane.

2. A tray comprising a frame having sides, means for suspending the frame in a medial bisecting plane, a pair of flanges extending from opposite sides of said tray and perpendicularly to said plane, and a counter-balance bar slidable in said pairs of flanges.

3. A tray comprising a frame having sides and separate goods and counter-balance supporting means, posts extending upwardly from the midpoints of opposite sides thereof, and a counter-balance slidable on said counter-balance supporting means transversely of said posts.

4. A tray comprising a frame having sides, posts extending upwardly from the midpoints of opposite sides thereof, flanges extending inwardly from said sides, and a counter-balance bar slidable on said flanges.

5. A tray comprising a frame having sides, posts extending upwardly from the midpoints of opposite sides thereof, pairs of flanges extending inwardly from said sides and parallel to the bottom plane of said frame, a counter-balance bar having its ends slidably received in said pairs of flanges, and a panel supported on the upper flanges.

6. A tray comprising a frame having sides, means for suspending the frame in a medial

bisecting plane, a pair of flanges extending from opposite sides of said tray and perpendicularly to said plane, and a counter-balance bar slidable in said pairs of flanges, and a panel supported on the upper flanges.

7. A display tray comprising a frame having side portions, a merchandise supporting platform mounted on said frame, a pair of suspension posts having their lower ends respectively connected to the central portions of two opposed side portions of said frame, and an adjustable counter-balance supported by said frame for adjustment transversely to a plane perpendicular to said platform and intersecting the latter along a line extending between said central portions.
